UNITED STATES PATENT OFFICE

ERIC N. NORDHEM, OF CHICAGO, ILLINOIS

HIGH TENSION CUT-OUT AND THE LIKE

Application filed June 6, 1930. Serial No. 459,601.

This invention relates to certain improvements in cut-outs especially intended for opening high tension circuits and the like. While the construction herein disclosed is especially intended for controlling high tension circuits and the like, still it will be understood that structures embodying the features of the present invention may also be used for the opening of other circuits. Therefore I do not intend to limit myself to the use of said features in connection with high tension circuits, although it will be understood that the design and construction are especially intended for this class of work.

One of the features of the invention relates to the provision of an arrangement in which the physical operation of opening the circuit is performed by power derived from a suitable compressed gas. This compressed gas may, for example, by compressed air, or carbon dioxide or nitrogen under compression, or any other suitable gas, preferably an inert gas of powerful arc extinguishing properties.

One object of the invention is to provide a construction in which use is made of a self-contained container for the compressed gas, which container constitutes a self-contained unit and can readily be set into place or removed from the remaining portions of the structure of the high tension cut-out. This self-contained unit may be readily set into place or removed from the remaining portions of the structure, thus making it possible to substitute a new container which has been charged with the appropriate gas under the desired pressure at some filling or charging station.

Another feature of the invention relates to the provision of an arrangement such that the releasing of the gas will be accomplished at the proper time very suddenly and through a relatively large opening so that a very powerful force may be generated for operating the circuit opening device. At the same time the arrangement is such that the device will be sensitive to the degree necessary to insure accurate operation and at the same time to avoid premature or improper functioning of the gas release.

A further object in this connection is to provide an arrangement such that the gas will normally be sealed into the container in a perfectly gas-tight manner so that there will be substantially no leakage or wastage of pressure therefrom. Consequently, the charged unit will maintain and retain its pressure for a long interval of time. This will also insure a definite certainty of operation at the critical time even when the device has been standing for a long interval without attention.

Another feature of the invention relates to the provision of an improved construction member whose movement serves directly and definitely to open the circuit. This movable contact member normally makes connection with stationary contacts under considerable pressure which entails the existence of a certain degree of friction which must be overcome at the instant the movement of the contact member commences. One of the objects of the invention is to provide an arrangement such that the gas pressure of the released gas is directed primarily against a piston of relatively large size so that a large operating force is generated at the commencement of the circuit opening operation. The movement of this piston of large area continues through a sufficient distance to insure a satisfactory disengagement of the friction parts. Another feature of the invention relates to the provision of another piston of smaller size in conjunction therewith so that the continued movement of the movable contact member for the purpose of completing the circuit opening operation through a considerable distance of travel does not entail the consumption of more than a relatively small additional amount of operating gas.

By the foregoing combination of parts, I am enabled to generate the necessary large initial operating force in combination with a greatly reduced total gas consumption for the production of the total desired amount of movement of the movable contact member.

Another feature of the invention relates to the provision of an arrangement such that a visual indication will be given of the condition of the device so that it is possible for

a person to ascertain immediately by examination of such indicator as to whether or not the device has functioned.

Another feature of the invention relates to 5 the provision of an improved means of retaining the movable contact member in the raised or circuit opened position, and for establishing connection therewith during the circuit opening operation.

10 In connection with the extinguishment of the arc by a quenching bath, it is noted that as the terminals are pulled apart to open the circuit, there form gas bubbles which are separated by layers or films of the liquid. 15 The gas of these bubbles is ionized and they are therefore of conducting quality. The quenching action of the bath is due to the layers or films of liquid between the bubbles. One feature of the present invention is to 20 place the bath under pressure greater than atmospheric so that the bubbles are reduced in size with consequent increase of thickness of the oil layers between the bubbles. The quenching ability of the bath is thus improved and the arc will be more quickly killed or extinguished.

Another feature relates to the provision of a device which can be very easily reset for another operation.

30 Other objects and uses of the invention will appear from a detailed description of the same, which consists in the features of construction and combinations of parts hereinafter described and claimed.

35 In the drawing:

Figure 1 shows a longitudinal section through a device embodying the features of the present invention, portions thereof being broken away in order to shorten up the figure.

40 Figure 2 shows a fragmentary section through the upper portion of the device taken at an angle of 45° to the section of Figure 1; Figure 2 may also be considered as a section on the line 2—2 of Figure 3, looking in 45 the direction of the arrows;

Figure 3 shows a top plan view of the device of Figures 1 and 2;

Figure 4 shows an offset section taken on the line 4—4 of Figure 1, looking in the direction of the arrows, the right hand portion of the figure being stepped down to the visual indication device.

Figure 5 shows a cross section on the line 5—5 of Figure 1, looking in the direction of the arrows; and

55 Figure 6 shows a fragmentary diagram showing the electrical connections of the device.

The arrangement illustrated includes a tubular or cylindrical body member 7 of glass or other suitable insulating material. A cap 8 having a flange 9, is provided for the lower end of the member 7, said lower end being set down into the flange 9 and sealed into place by lead or the like 10 in the customary

manner. Preferably, also, a washer or gasket 11 is placed at the lower end of the member 7 where it sets into the cap 8.

A collar member 12 has a downwardly depending flange 13 which receives the upper end of the tubular member 7, which is sealed in place by means of lead 14 or the like. Preferably, also, a gasket or washer 15 is set into place between the end of the tubular member 7 and the shoulder 16 of the collar 12. 70

A nipple 17 is threaded into the upper end of the collar 12 and projects beyond the same a sufficient distance to enable the charged compressed gas unit to be screwed into place.

80 A block 18 is set into the collar 12 and depends downwardly into the chamber 17; and a shoulder 19 is preferably formed in the collar 12 so as to receive a slight enlargement of the member 18 and thus prevent said member from dropping down.

85 The lower portion of the member 18 is provided with a pocket or chamber 20 of relatively large size. The lower end thereof is closed by a plug 21, but there is a series of openings 22 reaching laterally through the lower portion of the member 18 and communicating with the lower end of the chamber 20. For this purpose the plug 21 is preferably provided with an encircling groove 23 which communicates with the openings 22 90 and allow a very rapid transfer of gas into the chamber 20.

95 A large plunger 24 is located and works within the chamber 20 above the position of the plug 21.

100 The movable contact rod 25 extends down through a central opening 26 of the piston 24 and through a companion central opening of the plug 21.

105 There is a stationary contact member 27 having the stud 28 which reaches down and threads into a boss 29, extending up from the bottom cap 8. A series of contact fingers 30 reach upward from the member 27 and receive the lower end of the rod 25 when 110 the circuit is closed.

115 The upper end of the movable contact rod carries a head block 31. The member 18 is provided with a central bore 32 of proper size to receive the head block 31 as the movable contact rod 25 travels upwards, the head block 31 travelling through the bore 32 with a loose fit. A plug 33 is screwed into the upper end of the member 18 so as to close the bore 32; and preferably a block 34 of leather, felt, or other suitable material for cushioning is placed on the lower end of the plug 33 so as to receive the impact of the head block 31 as the rod 25 reaches the upper end of its travel. 120

125 The member 18 is provided above the position of the cylinder opening 20, with an opening 35 of somewhat reduced size. A member 36 is set into said opening 35 with a tight fit and has a series of upwardly extending 125

contact fingers 37 which normally make contact with the head block 31 when the circuit is closed. When the rod 25 is projected upwards the head block 31 travels away from the fingers 37 and into the bore 32.

The rod 25 also carries a piston block 38 of substantially the same size as the head block 31. The lower face of said piston block 38 is preferably bevelled and makes a nice fit 10 against the upper portion of the central opening 26 of the piston 24.

The member 18 is of somewhat smaller external diameter than the internal size of the cylindrical member 7. Normally the device 15 is filled with a suitable quenching liquid up to substantially the level 39 which is slightly below the lower end of the member 18. Preferably also, a block 40 is secured to the bottom face of the block 21, said block 40 having a 20 longitudinal slotted opening 41 which leaves on one side a relatively long spring member 42. The block 40 is provided with a seat 43 directly opposite to the center of the spring member 42; and the movable contact rod 25 25 is grasped between the spring portion 42 and the portion 43 with sufficient friction to prevent the contact rod from dropping down while at the same time not interfering with its upward movement when projected upwards by the circuit opening operation.

When the device is to be operated, compressed gas is suddenly delivered down through the annular space 44 between the member 18 and the cylindrical member 7. 30 This compressed gas flows through the openings 22 and 23 and against the bottom faces of the pistons 24 and 38. Of course the compressed gas also reacts against the surface of the liquid 39 but the same is sufficiently held 35 by the strength of the member 7.

The compressed gas thus exerts a powerful upward force against the large piston 24 whose area supplements that of the smaller piston 38. The vertical dimension of the 40 cylindrical chamber 20 is sufficient to allow for the necessary upward movement of the rod 25 to disengage from the contacts 30 and 37. Then the movement of the piston 24 is arrested. The smaller piston 38 then enters 45 through the member 36 and at the same time the head block 31 enters the bore 32 and travels upward therein. The result is that the gas pressure from that time forward is exerted on the relatively small area of the piston 31. The area thereof is sufficient to insure 50 the desired amount of upward force to continue upward travel of the contact rod 25 until arrested by the pad 34; and due to this relatively small size the amount of gas consumption necessary for this portion of the 55 operation is relatively small.

The compressed gas for bringing about the foregoing operation may be derived from any suitable source. In the present arrangement 60 I have provided a flask or container therefor

which is removably attached to the upper portion of the structure. This includes a sleeve or collar 45 which can be threaded onto the upper end of the nipple 17. This collar 45 terminates in a horizontal flange 46 from which there is a tubular section 47 reaching upwardly above the flange 46. A block 48 is secured into the upper end of the tubular section 47, said block having a downwardly extending bore 49 which reaches partly through the block. Opposite to this bore 49 the block 48 is externally grooved as shown at 50 so as to provide a very thin wall at that point. Consequently, by forcing the lower end 51 of the block sidewise, it can be easily broken off 70 at the position of the groove 50. A stem 52 is threaded into the lower portion 51, said stem reaching down through the tubular section 47 to the lower end thereof. 75

A cap shell 53 is set over the tubular section 47, the lower end of said cap shell reaching down around the collar 45 to which it is secured in gas tight fashion. The space between the cap shell 53 and the tubular section 47 constitutes a chamber for the reception of compressed gas. This chamber can be easily charged in any convenient manner. In the construction illustrated, there is provided a check-valve 55 which is normally set by a spring 56. After the compressed gas has been delivered into the chamber, the check-valve will retain it therein, but a screw 57 may then be screwed into the lower portion of the member 54 and secured by soldering or otherwise. 80

Reaching downwardly within the tubular section 47 there is a spring arm 58. The upper end thereof is rigidly secured to the tubular section 47. The lower end of this spring arm 58 is normally retained under tension by a tension wire 59, one end of which extends through a slot 60 in the lower end of the arm 58. The other end of said tension wire is connected into a plug 61 which passes through an insulating sleeve 62 in the wall of the member 45. When a current of sufficient intensity flows through the wire 59, said wire burns off, thereby releasing the spring arm 58. Said spring arm then exerts a sufficient lateral pressure on to the pin 52 to suddenly deflect the same to one side and thus break off the lower portion 51 of the member 48. 100

Preferably a plate 63 is set into the collar 45 before the member 45 is screwed on to the same, said plate 63 being provided with numerous perforations 64 through which the gas is allowed to flow down when the device is released. 105

The gas flowing down through the openings 64 and past the nipple 17 continues on down through passages 65 to the upper end of the space 44 referred to already.

The plate 63 is for the purpose of preventing the pin 52 and other parts from dropping down into the lower portion of the device when it functions.

There is a removable hood 66 which can be set down over the chamber 53. This hood 66 is of rectangular form, its inner surface being insulated by a paper layer or the like 5 84, but there is an inwardly reaching insulating collar 67 at the lower end of said hood, which collar 67 has a circular central opening to receive the chamber 53. The upper portion of the hood 66 is inturned as shown 10 at 68 and is provided with a central circular opening which receives a circular block of insulating material 69. The top face of this block of insulating material 69 carries a semi-circular plate 70. The upper portion 15 68 of the hood 66 is inturned as shown in Figure 1 and terminates in a member 71 opposite to the central portion of the member 70. The fuse 72 normally connects the central portion of the member 70 to the block 71 20 so that the current normally flows from the hood 66 across the member 71, across the fuse to the member 70. The ends of the member 70 connect by screws 81 and 82 into blocks 83 in the roof of the shell 53. Consequently, the current flows from the member 70, down through the screws 81 and 82 into the shell 53 and thus into the member 25 45, nipple 17, and collar 12. The current then flows down through the block 18, contacts 37, head block 31, movable contact rod 20 25, contacts 30, and into the lower cap 8. 25

There is a plate 73 secured to the bottom face of the insulating block 69, said plate 30 35 73 being of angular form as best shown in Figure 3. A spring finger 74 extends downwardly from the plate 73 in one corner of the hood 66, the lower end of said spring finger normally making contact with the outer end of the block 61 when the hood 66 is 40 45 in place. The plate 73 has an upwardly extending stud 75 which reaches up through the insulating block 69 to a position directly beneath the fuse 72, with which however, it does not normally make contact there being 50 55 preferably a layer of paper between these parts. When the fuse 72 blows, the arc so created, and the high tension current, jump from the end of the fuse 72 or the stud 71, to the stud 75 and thence down through the plate 73 and spring finger 74, through the tension wire 59, spring finger 58, tubular section 47, and member 45, etc. This causes the full overload current to be suddenly diverted into the tension wire 59 which thus 60 65 burns off and relieves the spring finger 58. This immediately causes a large lateral pressure against the finger 52 and breaks off the block portion 51 at the position of the groove 50 to release the gas as already explained.

It will be understood that the compressed gas container can be readily removed and a new unit set into place by merely unscrewing the collar 45 from the upper end of the 65 70 nipple 17. When the collar 45 has been un-

screwed from the nipple 17, the grid plate 63 comes off with the collar 45, the plug 33 may be unscrewed and a rod or other tool may be introduced for the purpose of pushing the movable contact rod 25 downwardly 70 to reset the same.

In order to give a visual indication of the condition of the device, I have provided a laterally extending gas passage 76, which reaches from the upper portion of the bore 75 32 to a groove 77 formed around the upper portion of the block 18 above the position of the shoulder 19. This groove 77 communicates with an outwardly extending passage 78 in the member 12, which passage 78 is 80 normally closed by a relatively thin wall 79 of mica or paper, preferably colored, held in place by a flange 80. The upward travel of the rod 25 together with the head block 31 will drive air or gas ahead of the same 85 and out through the passages 76 and 78, thereby bursting the diaphragm 79 and giving the desired visual indication.

I wish to point out that by the use of compressed gas for insuring the movement of the movable contact member, I am able to secure a much more rapid and instantaneous action than can be obtained by the use of a spring. This is because the spring when released must first overcome the inertia of 90 those portions of it which undergo movement, being the entire mass of the spring except the very end portion which is fastened stationary. The net inertia of the spring can be mathematically calculated taking into account the fact that the different portions of it are accelerated at different rates. On the contrary, where compressed gas is used, the only inertia of substantial amount to be overcome is the inertia of the 100 piston which is the element sought to be moved. The inertia of the gas itself is relatively insignificant.

While I have herein shown and described only a single embodiment of the features of 110 my present invention, still I do not intend to limit myself thereto except as I may do so in the claims.

It will be noted that upon operation of this device the quenching liquid is subjected to a 115 hydrostatic pressure greater than atmospheric by an amount equal to the gas pressure which is exerted against the pistons 24 and 38. This is also equal to the pressure of the gas pressing down on the surface of the 120 quenching liquid.

Owing to the above system, the quenching liquid itself is subjected to a considerable increase of hydrostatic pressure at the very time that the arc is being extinguished, namely, at the time the rod 25 separates from the contact fingers 30. This results in substantial reduction of the volume and size of the gas bubbles so that the thickness of the films or layers of quenching liquid between the 125

bubbles is correspondingly increased. For these reasons a very much more perfect and quicker acting extinguishing operation is produced than would otherwise be the case.

I claim:

- 5 1. In a device of the class described, the combination of a cylindrical chamber of insulating material, a closure for the lower end thereof, a stationary contact at said lower end, a ferrule secured to the upper end of said chamber, a downwardly extending member secured to said ferrule and having a central longitudinally extending cylindrical bore of small size terminating at its lower end in a cylindrical bore of enlarged size, a vertically movable contact rod having its lower end working in conjunction with the stationary contact aforesaid, and having on its upper portion a piston enlargement adapted to travel within the cylindrical bore of small size, an enlarged piston surrounding said contact rod and of proper size to travel within the cylindrical bore of enlarged size in sealing fashion, said enlarged piston bearing against and lifting against the piston of smaller size aforesaid, a vent opening communicating with the upper end of the cylindrical bore, a diaphragm sealing the outer end of said vent opening and subject to rupture when the piston rises through the bore of smaller size to thereby give a visual indication, quenching liquid within the cylindrical chamber below the pistons, there being suitable passages for gas in the upper portion of the device communicating with the space beneath the pistons and above the contained liquid, together with a removable sealed container for compressed gas removably connected to the upper portion of the device and in communication with the passages aforesaid, substantially as described. 70
- 10 2. In a device of the class described, the combination of a cylindrical chamber of insulating material, a closure for the lower end thereof, a stationary contact at said lower end, a ferrule secured to the upper end of said chamber, a downwardly extending member secured to said ferrule and having a central longitudinally extending cylindrical bore of small size terminating at its lower end in a cylindrical bore of enlarged size, a vertically movable contact rod having its lower end working in conjunction with the stationary contact aforesaid, and having on its upper portion a piston enlargement adapted to travel within the cylindrical bore of small size, an enlarged piston surrounding said contact rod and of proper size to travel within the cylindrical bore of enlarged size in sealing fashion, said enlarged piston bearing against and lifting against the piston of smaller size aforesaid, there being suitable passages for gas in the upper portion of the device communicating with the space beneath the pistons, together with a removable sealed container for compressed gas removably connected to the upper portion of the device and in communication with the passages aforesaid, substantially as described. 75
- 15 3. In a device of the class described, the combination of a cylindrical chamber of insulating material, a closure for the lower end thereof, a stationary contact at said lower end, a ferrule secured to the upper end of said chamber, a downwardly extending member secured to said ferrule and having a central longitudinally extending cylindrical bore of small size terminating at its lower end in a cylindrical bore of enlarged size, a vertically movable contact rod having its lower end working in conjunction with the stationary contact aforesaid, and having on its upper portion a piston enlargement adapted to travel within the cylindrical bore of small size, an enlarged piston surrounding said contact rod and of proper size to travel within the cylindrical bore of enlarged size in sealing fashion, said enlarged piston bearing against and lifting against the piston of smaller size aforesaid, there being suitable passages for gas in the upper portion of the device communicating with the space beneath the pistons, together with a removable sealed container for compressed gas removably connected to the upper portion of the device and in communication with the passages aforesaid, substantially as described. 80
- 20 4. In a device of the class described, the combination of a stationary contact, a movable contact rod working in conjunction therewith, a stationary cylinder having a bore of small size terminating at its lower end in a short bore of enlarged size, a piston of small size on the rod adapted to work in the bore of small size, a piston of enlarged size surrounding the rod and located beneath the piston of small size and working in the bore of enlarged size, means for arresting movement of the large size piston prior to arrest of movement of the piston of small size, together with means for introducing gas under pressure beneath the piston of enlarged size for the purpose of commencing a circuit opening operation, the movement of the rod and piston of small size continuing into the bore of small size after arrest of movement of the piston of enlarged size, substantially as described. 85
- 25 5. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 90
- 30 6. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 95
- 35 7. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 100
- 40 8. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 105
- 45 9. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 110
- 50 10. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 115
- 55 11. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 120
- 60 12. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 125
- 65 13. In a device of the class described, the combination of a stationary contact, a movable contact rod working in conjunction therewith, the rod breaking connection from the stationary contact after a limited amount of movement, a stationary cylinder having a bore of small size terminating at its lower end in a bore of enlarged size and length substantially as great as the amount of rod movement for such disengagement, a piston 130

of small size on the rod adapted to work in the bore of small size, a piston of enlarged size surrounding the rod and located beneath the piston of small size and working in the bore of enlarged size, means for arresting movement of the piston of large size prior to arrest of movement of the piston of small size, together with means for introducing gas under pressure initially beneath the piston of enlarged size for commencing a circuit 10 opening operation, the movement of the rod and piston of small size continuing into the bore of small size after arrest of movement of the piston of enlarged size, substantially as described.

6. In a device of the class described, the combination of a stationary contact, a movable contact member working in conjunction therewith, the arrangement being such that the parts are in engagement through a limited distance of travel, together with means for disengaging the movable contact including a pair of cylinders and pistons therein, one cylinder and piston being of larger size than the other cylinder and piston, means for arresting movement of the piston of large size prior to arrest of movement of the piston of small size, means for initially introducing gas under pressure into engagement with both of said pistons to commence the operation, and for thereafter continuing introduction of the fluid under pressure into the cylinder and piston of smaller size, substantially as described.

7. In a device of the class described, the combination of a stationary contact and a movable contact therefor, said parts normally being in engagement with each other throughout a limited range of movement of the movable contact, together with means for initiating and continuing movement of the movable contact, said means comprising a pair of cylinders and pistons of different sizes, means for initially introducing fluid under pressure into the cylinder and piston of larger size to initiate the movement, means for arresting movement of the piston of large size prior to arrest of movement of the piston of small size and for thereafter continuing introduction of the fluid under pressure in the cylinder of smaller size to keep the movement throughout a desired length of travel, substantially as described.

8. In a device of the class described, the combination of a stationary contact, a movable contact rod having frictional engagement with the stationary contact throughout a limited range of movement, together with means for disengaging said rod from said contact and separating the parts a desired distance from each other, said means including a pair of cylinders and pistons, means for initially introducing fluid under pressure against both of the pistons to establish 60 an initial force corresponding to both of

them, means for arresting movement of the piston of large size prior to arrest of movement of the piston of small size and means for thereafter continuing introduction of said fluid under pressure against the piston of smaller size to maintain the movement throughout the desired distance of travel for separation of the movable and stationary contacts from each other, substantially as described.

9. In a device of the class described, the combination of a stationary contact, a movable contact rod having frictional engagement with the stationary contact throughout a limited range of movement, together with means for disengaging said rod from said contact and separating the parts a desired distance from each other, said means including a pair of cylinders and pistons, of different sizes, means for initially introducing fluid under pressure against the piston of larger size to thereby initiate disengaging movement of the movable contact from the stationary contact, means of arresting movement of the piston of large size prior to arrest of movement of the piston of small size and means for thereafter continuing introduction of fluid under pressure against the piston of smaller size to thereby separate the movable and stationary contacts a desired distance from each other, substantially as described.

10. In a device of the class described, the combination of a stationary and movable contacts, a cylinder, a piston working therein and connected to the movable contact, and means for actuating said piston to move the contact for the purposes of opening the circuit, said means including a sealed cartridge containing fluid under pressure, said cartridge including a rupturable nipple, spring means in position to rupture said nipple when said spring means is released, a fusible tension link normally resisting said spring means, and means for diverting current into said fusible tension link under overload conditions, substantially as described.

11. In a device of the class described, the combination of the stationary and movable contacts, a cylinder and piston working therein, said piston connected to the movable contact, together with means for introducing fluid under pressure into the cylinder to actuate the piston under overload conditions, said means including a sealed cartridge having compressed fluid therein, a removable wall section for said cartridge which when removed permits exit of compressed fluid into the cylinder to actuate the piston, and means operable under overload conditions for causing removal of said wall section for the purpose specified, substantially as described.

12. In a device of the class described, the combination of a movable contact rod adapted to make and break connection, piston and

cylinder means in conjunction therewith, there being passages for the introduction of compressed gas for the operation of said pistons, together with means for introducing compressed gas into said passages to actuate the device under overload conditions, said means including a sealed cartridge for the compressed gas, a nipple constituting a portion of the gas inclosure of said cartridge and rupturable when deflected laterally, spring means for causing lateral deflection thereof for the purpose of rupturing the device to release the contained gas, and a fusible tension element for restraining the spring means aforesaid and normally preventing rupture of the device, said tension means constituting a portion of the circuit under overload conditions, substantially as described.
